Hewlett-Packard Company, Palo Alto, Calif., a
corporation of California

Filed Oct. 22, 1964, Ser. No. 405,800
6 Claims. (Cl. 346—74)

ABSTRACT OF THE DISCLOSURE

Electrosensitive recording method and means uses diffusion impurities in contiguous conductive layers to provide low ohmic contact therebetween and also uses a local source of heating to preheat or bias the electrosensitive recording medium for producing a contrasting record in response to the application of a small additional amount of energy in the form of an applied electrical writing signal.

It is an object of the present invention to provide an improved electrosensitive recording medium which responds to lower voltage writing signals of the order of 1 to 3 volts.

It is another object of the present invention to provide an electrosensitive recording medium which may be biased below recording levels by a source of energy to decrease the power required in the writing signal to produce a recording.

It is another object of the present invention to provide an improved method of electrosensitive recording.

In accordance with the illustrated embodiment of the present invention, a very low voltage electrosensitive recording medium is produced by treating a conductive base layer disposed on backing material to form an ohmic contact between a surface layer of heat-sensitive material and the base layer. This overcomes the effects of any barrier layers which form between the base layer and the surface layer and presents sufficiently high conductivity to applied writing signals to produce contrasting marks in response to applied writing signals as low as 1 to 3 volts.

These and other objects of the invention will be apparent from a reading of this specification and an inspection of the accompanying drawing which shows electrosensitive medium and recording apparatus according to the present invention.

In the drawing, relative motion of the recording medium 9 with respect to the electrodes 11, 13 may be produced by moving the recording medium 9 and electrodes 11, 13 at dissimilar velocities. Writing signals from source 15 are applied to the electrodes 11, 13 disposed in contact with the surface of recording medium 9 through switches 17, 19 which are actuated by writing controls 21, 23. Contrasting lines or marks 25 are produced on the medium 9 in response to the writing signals as the electrodes pass along the surface. The electrosensitive recording medium 9 is prepared according to one embodiment of the present invention as follows: aluminum is alloyed with indium in an amount typically of about 1 to 5 percent but less than 20 percent by weight. The alloy is vapor-deposited or laminated onto suitable backing material 27 such as paper or plastic film using well-known methods to form a thin conductive base layer 29. Other elements such as gallium, tin or other tri-valent electron donors may also be used in place of (or in addition to) the indium.

A conductive surface coating 31 comprising a heat-sensitive material which changes color at elevated temperatures is deposited on the base layer 29 using such conventional techniques as spraying or rolling. The sur-

2

face coating 31 may be prepared according to one embodiment of the present invention by combining 100 grams of indium-doped zinc oxide which acts as a white pigment as well as an electrical conductor, 62.5 grams of a suitable binder such as Lucite No. 2040, 137 milliliters of a solvent such as xylene or toluene and 25 grams of heat-sensitive substance formulated using four parts by weight of a heavy metal salt such as nickel acetate or nickel stearate to one part by weight of an alkaline earth metal sulfide such as calcium sulfide, barium sulfide or the like.

Other heat-sensitive substances may be formulated using 7.5 parts by weight of nickel palmitate, 2.5 parts by weight of barium or calcium sulfate and 1 part by weight of stearic or palmitic acid. Still another heat-sensitive substance may be formulated using 5 parts by weight of a stearate of a metal such as cobalt, copper, lead, magnesium, manganese, mercury, nickel or zinc and 1 part by weight of diphenylcarbozone. Of course, it will be appreciated by those skilled in the art that any heat-sensitive material including azo, diazo and leuco dyes (the latter dye being less light-sensitive than the azo and diazo dyes) may be used in the surface coating material.

This coating material is rolled onto the base layer 29 to a wet thickness of about 3 mils and is dried at a temperature below the threshold value at which the color transition in the heat-sensitive material takes place. The surface layer 31 thus formed comprises a matrix of heat-sensitive and electrically conductive materials which are bonded to the base layer 29.

30 It is believed that the base layer 29 which is an alloy of aluminum becomes coated with a discontinuous film of oxide when exposed to air during the fabrication process. This oxide layer acts as an insulator which decreases the conductivity of the recording medium from the surface 35 layer 31 to the base layer 29. This increases the amplitude of writing signal necessary to provide sufficiently high current density to produce a contrasting record on the surface layer. The indium in the alloy base layer is believed to retard development of an oxide coating and to

40 "wet" the contiguous surfaces of the base layer and surface layer through regions of discontinuity in the oxide film, thereby forming a low ohmic resistive contact between the two layers. A minute amount of diffusion of the indium into the surface layer is also believed to occur, 45 thereby further increasing the conductivity of the ohmic contact. The high conductivity of the recording medium thus reduces the writing signal amplitude required to produce a contrasting record on the surface layer 31.

The writing signal amplitude required to produce a 50 contrasting record may be reduced further according to one embodiment of the present invention by providing a biasing signal for the heat-sensitive surface layer. As is commonly known, leuco dyes and other mentioned heat-sensitive compounds used in the surface layer 31 change 55 composition, and hence, change color rather abruptly with temperature. Thus the surface layer 31 may be elevated in temperature by heating element 30 disposed near the electrodes 11, 13 to a temperature just below the threshold value at which the color transition in the dye

60 occurs. This transition may occur typically within a 5° C. range so that the internal or joule heating provided by the writing signal need only produce a small increment in temperature. Considerably less power per electrode is then required from the writing signal to elevate the 65 temperature of record regions on the surface layer 31 above the transition temperature to produce a contrasting record.

Thus electrosensitive recording may be achieved using the recording medium and apparatus of the present invention with writing signals of a few volts at very low power levels, typically 100 milliwatts or less per electrode. This 70 may be due in part to the highly conductive ohmic con-

tact formed between the base and surface layers by the indium in the base layer alloy and in part to the locally applied heat which biases the heat-sensitive material in the surface layer to a temperature just below the temperature at which the heat-sensitive material undergoes a color transition. 5

I claim:

1. Recording apparatus comprising:
a base layer of conductive material including an alloy of aluminum and an element selected from the group comprising indium, gallium and tin; 10
a conductive surface layer disposed on said base layer and including a heat-sensitive material which changes color at elevated temperatures;
said element diffusing into said surface layer to form 15
an ohmic contact between said surface layer and said base layer;
whereby a writing signal applied to said surface coating provides current flow therethrough with sufficient current density to elevate the temperature of local 20
regions thereof to produce a color change in such regions.
2. Recording apparatus as in claim 1 wherein said surface layer includes a heat-sensitive material selected from the group comprising azo, diazo and leuco dyes and a 25
material which shows high electrical conductivity.
3. Recording apparatus comprising:
a backing layer;
a conductive layer on said backing layer including an alloy of aluminum and indium in a ratio of less than 30
one part indium to four parts aluminum;
a conductive surface layer disposed on said conductive layer;
said surface layer including a heat-sensitive material selected from the group comprising azo, diazo and 35
leuco dyes which change color at elevated temperatures;
the indium in said conductive layer diffusing into said surface layer to form an ohmic contact between said 40
surface layer and said conductive layer;
whereby a writing signal applied to said surface layer provides current flow therethrough with sufficient current density to elevate the temperature of local 45
regions thereof to produce a color change in such regions.
4. Recording apparatus comprising:
a base layer of conductive material;
a conductive surface coating disposed on said base layer and including a heat-sensitive material which changes color at elevated temperatures; 50
a heat source disposed near said surface coating in a selected region for heating said surface coating to a temperature below the elevated temperature at which said heat-sensitive material changes color;
a source of writing signal; and

an electrode connected to said source and disposed to apply a writing signal to said surface coating with sufficient amplitude to produce a current flow therethrough with sufficient current density to increase the temperature of local regions of the surface coating near the electrode to a temperature above the elevated temperature at which said heat-sensitive material changes color, thereby to produce a contrasting record in such regions.

5. Recording apparatus as in claim 4 wherein:
said heat-sensitive material in said surface layer is selected from the group comprising azo, diazo and leuco dyes.
6. Recording apparatus comprising:
a base layer including an alloy of aluminum and an element selected from the group comprising indium, gallium and tin;
a conductive surface coating disposed on said base layer and including a heat-sensitive material which changes color at elevated temperatures;
said element being diffused into the surface coating to form an ohmic contact between said surface layer and said base layer;
a heat source disposed near said surface coating in a selected region for heating said surface coating to a temperature below the elevated temperature at which said heat-sensitive material changes color;
a source of writing signal; and
an electrode connected to said source and disposed to apply a writing signal to said surface coating with sufficient amplitude to produce a current flow therethrough with sufficient current density to increase the temperature of local regions of the surface coating near the electrode to a temperature above the elevated temperature at which said heat-sensitive material changes color, thereby to produce a contrasting record in such region.
